SYSTEM OF CONTROL

Edgar M. Bouton, East Pittsburgh, Pa., assignor
to Westinghouse Electric & Manufacturing
Company, a corporation of Pennsylvania

Application August 14, 1924, Serial No. 731,921

19 Claims. (Cl. 172—152)

My invention relates to systems of control and it has particular relation to systems that are employed for elevators, hoists and similar applications.

5 An object of my invention is to provide means for effecting more accurate control of an elevator car at each floor or landing, regardless of load conditions, than has been possible in prior elevator-control systems.

10 Another object of my invention is to provide a variable-voltage system of control wherein the voltage applied to the motor may be maintained at a constant value corresponding to a predetermined hoisting speed during upward or 15 downward travel, if desired.

A further object of my invention is to avoid the necessity of "inching" the elevator by insuring that the car shall always stop in such position that its floor and the landing floor shall 20 be in substantially the same plane, thus making a positive automatic landing stop.

25 Another object of my invention is to insure smooth and accurate control of an elevator by means of a single hoisting motor and by maintaining an uninterrupted supply of energy to the motor at all times during normal operation.

My invention will be described in connection with the accompanying drawings in which

Figure 1 is a diagrammatic representation of 30 the main circuits and apparatus embodying my invention;

Fig. 2 is a diagrammatic view of certain control features employed in connection with the system of Fig. 1;

35 Fig. 3 represents a relay or contactor employed in connection with my invention; and

Fig. 4 represents, diagrammatically, the relative positions of several floors to be served by the elevator and the relative location of certain 40 shoes or armatures that are adapted to control the relays illustrated in Fig. 3.

With reference to Figs. 1 and 2, my invention comprises, preferably, a variable-voltage system of control embodying a hoisting motor 1 having 45 a separately excited field-magnet winding 2. A generator 3 is connected in a "loop" circuit with the motor and is also provided with a separately excited field-magnet winding 4, which may be controlled, in a familiar manner, by reversing switches 5, 6, 7 and 8. The generator is provided also with a cumulative series field-winding 9 having proper characteristics to insure a substantially constant generator voltage for any given excitation of the separately excited winding. The generator is driven in a familiar man-

ner by any suitable means, such as the illustrated induction motor 10, and an exciter 11 is mounted on the generator shaft for the purpose of supplying the necessary constant voltage for the control of various magnetic switches, 5 field windings and a suitable electro-magnetic brake 12.

Variable excitation of the generator 3 is accomplished by means of an external resistor 13, portions of which are successively excluded from 10 circuit by means of a plurality of field relays 14, 15, 16 and 17, in a manner to be herein-after set forth. Another resistor 24 is provided to be connected, by means of a relay 25, in parallel relation to the separately excited generator field-winding 4. Various "landing" 15 switches 26 to 31, inclusive, of the well-known cam-operated type, are mounted on the car for controlling the elevator car in accordance with its position in the hatchway. Switches 26, 27, 20 28 and 29 are of the normally open contact type while switches 30 and 31 are of the normally closed contact type.

A retiring magnet 32 is associated with switches 26, 28 and 30 to hold these switches 25 in their normal positions, (switches 26 and 28 closed and switch 30 open) during energization of the coil. A magnet 33 performs a similar function with respect to switches 27, 29 and 31.

The cams engageable with the rollers of these 30 switches maintain them in the same positions as does their coils until the movement of the car toward the floor with which the cams are associated causes the rollers to move off the cams, thus allowing the respective switches to 35 assume their normal position.

In Fig. 2, I have illustrated control connections for energizing the operating coils of the floor relays 35 to 38, inclusive, of the type illustrated in Fig. 3. The relays 35 to 38 are energized by means of contact members 41, 42, 43 and 44, respectively, of the car-switch 45.

Referring to Fig. 3, it will be seen that each of these relays 35 to 38 comprises an armature 46, an actuating coil 47, and a core 47a formed 45 substantially H-shaped with legs 47b somewhat longer than the legs 47c.

Energization of the coil 47 causes attraction of the armature 46 and thus closes contact between contact members 46a.

Relays 35 to 38 are mounted on the elevator car for movement therewith (see Fig. 4) past groups of magnetizable iron plates 51, 52, 53 and 54, one of these groups being associated with each floor past which the car operates. 55

Plate 54 cooperates with relay 35 to effect a release of the armature 46 as the relay passes the plate by diverting the magnetic flux in the core 47a through the short path defined by legs 47c. 5 Plates 51 to 53 perform a like function for the remaining relays.

My invention will be best understood from the following description of its operation. Assuming the car to be at the first-floor level and the control apparatus in its illustrated and inoperative condition, the car may be started toward the fourth floor, for example, by closure of car-switch contact members 55. The up direction relay 56 is thereby closed, its operating coil being connected to the illustrated line conductors, whereupon reversing switches 5 and 7 and brake-releasing relay 57 are closed. The closure of switches 5 and 7 connects the generator field winding 4 in circuit with field resistor 13 across the exciter 11. 20

When the car switch is actuated to its full-speed position, contact members 42 and 44 are closed to operate field relays 25, 15 and 16 and floor relays 36 and 38. In addition to these field relays, auxiliary relays 59 and 61 are closed for a purpose to be disclosed later. The operating circuit for these relays extends from the positive line conductor through operating coils 62 to 66, inclusive, contact members 42 and landing switches 30 and 31 (closed at this instant) to the negative line conductor. The operating circuit for field relay 16 and floor relay 38 extends from the positive line conductor through coils 67 and 68, car switch contact members 44 and landing switches 30 and 31 to the negative line conductor. Relay 59 operates to energize coils 32 and 33 and thus causes switches 26, 27, 28 and 29 to close and switches 30 and 31 to open. 30

40 Switch 26 completes a holding circuit for reversing switches 5 and 7 independent of up relay 56. Switches 28 and 29 complete a circuit for relay 17. However, relays 35 to 38 have completed self holding circuits by way of conductor 78 and are, therefore, maintained energized independent of switches 30 and 31.

The operation of relay 25 disconnects resistor 24, which was previously in shunt to the generator field winding 4, thus increasing the field 50 excitation. The circuit for the separately excited field winding extends from the positive line conductor, through conductor 90, reversing switch 5, conductors 91 and 92, field winding 3, conductor 93, the coil of relay 34, conductors 94, 95 and 96, reversing switch 7, conductor 97, and resistor 13 to the negative line conductor. The relay 25, therefore, normally completes a shunt circuit for the field winding between conductors 91 and 94. The closure of relays 15 and 16 effects further strengthening of the generator field by excluding portions of resistor 13 from circuit. Relay 17, closed through landing switch 28 or landing switch 29 excludes another portion of resistor 13. Maximum field excitation is 60 in this manner provided for the generator 3 and the motor 1 is thereby accelerated to full speed. At this time, relay 34 is energized by the current traversing the now fully excited field winding 4 of the generator 3 and this relay completes a circuit for the retiring magnets 32 and 33 independent of relay 59 to insure retirement of the switches 35 to 38 when the field current reaches a predetermined value; in other words, when the car is operating under full speed conditions. 70

If it is desired to stop the elevator at the fourth floor, the car switch may be returned to its "off" position after the car, in its upward travel, passes the shoe 54 adjacent to the second floor. It should be noted that the movement of the car is now independent of the car switch, and as previously described a holding circuit for the up reversing or directional switches 5 and 7 extends from the positive line conductor through the operating coils of switches 5, 7 and 10 57, interlocks 6-out and 7-in, landing switch 26, conductor 76 and knife switch 77 to the negative line conductor. Interlocks 6-out and 6-in indicate the corresponding "in" or "out" positions of the switches 6 and 7 to close the interlocks. 15

The holding circuit for relays 25, 15, 59, 61 and 36, extends through relay coils 62 to 66, relay 36, conductor 78 and knife switch 77 to the negative line conductor. A holding circuit 20 for relay 16, extends through coils 67 and 68, relay 38 and conductor 78. Therefore, high speed connections are maintained until the car passes the shoe 54 adjacent to the third floor. This shoe establishes a demagnetizing circuit 25 and effects the opening of relay 38. Field relay 16 is thereby de-energized to insert a portion of resistor 13 in the generator field circuit. The elevator speed is thus reduced and when the car passes the shoe 53, below the fourth floor, 30 relay 36 is opened, which thereby permits relay 25 to close and relays 15, 59 and 61 to open. This operation of field relays 25 and 15 effects further reduction in the generator field strength to correspondingly reduce the car speed. The exact location of the demagnetizing shoes with respect to the distance from the fourth floor depends upon the maximum car speed and the time required to effect slow-down, as will be understood. 40

When relay 34 opens, coils 32 and 33 are de-energized and the several limit switches thus become effective subject to the operation of the associated cams to further slow down and stop the elevator. The opening of limit switches 26 15 and 29 effects the opening of field relay 17 and, as the car approaches the fourth floor level, limit switch 26 opens to de-energize the coils 5', 7' and 57' of reversing switches 5 and 7 and brake relay 57, thus bringing the car to rest 50 at the floor level.

The cumulative series winding 9 on the generator 3 compensates for variations in the load to be lifted or lowered so that the car always stops substantially level with the floor. I find, 55 however, that it is necessary to compensate for the "magnetization curve" of the generator field on account of the hysteresis loop. That is to say, when starting from rest, a definite slow speed corresponding to the first operating point 60 is attained at a given field flux ϕ , which requires a field current corresponding to NI_2 ampere-turns. When slowing down from high speed to the first or low-speed point, to obtain the same definite speed the same field flux ϕ is produced 65 at less ampere-turns, corresponding to NI_1 . For this reason I provide means, comprising a relay 14, which is normally closed in its lower position, to exclude a portion of field resistor 13 on the first point of the car switch. A field current I_2 thereupon traverses the generator field-winding. 70

During high-speed operation, relay 61 is closed through car-switch contact members 42, whereupon relay 14 is picked up and maintains 75

a holding circuit for itself, thereby inserting said portion of resistor 13 in circuit with the generator field winding to reduce the field current to a value equal to I_1 . Thus the full field strength required upon the initial starting of the car is supplied and the field strength is reduced when the car is operating under high speed conditions. The self holding circuit for relay 14 is broken by the deenergization of relay 61 when the floor relay 35 (or 36) is opened as the car is stopped.

The series cumulative field-winding provides a flat compounding-effect so that the speed of the elevator motor at slow speed is substantially independent of the load in the car. It will be understood, of course, that the load current varies from that required to lift a full car to that which passes through zero and becomes a current of regeneration, when lowering a fully loaded car. This wide variation in load tends to produce poor speed regulation and raises a problem in elevator control which has resulted in the production of control systems usually termed "floor-levelling" systems. Such systems usually employ a separate source of power to insure accurate stopping and to return the car to the desired level in case of overtravel. Such arrangements are undesirable, in passenger service, at least, because of the time lost in accomplishing the desired result. It will be seen that, by the use of my system, overtravel is prevented and no "levelling" is required, inasmuch as an automatic or direct landing is effected.

Downward movement of the car is effected in a manner similar to that already described upon the closure of down relay 19, which is controlled by car switch members 81 to operate reversing switches 6 and 8 and brake relay 80. When the car switch is actuated to close "down" contact members 81, 41 and 43 for this direction of travel, the field relays are controlled through floor relays 35 and 37, instead of through relays 36 and 38, so that, in approaching a floor, high-speed relay 37 is first opened to drop out field relay 16 and, thereafter, floor relay 35 is opened to de-energize the coils of field relays 25 and 15. The final slow-down and stop are thereafter made as previously described for the upward movement of the elevator.

The motor cannot be "plugged" or reversed before reaching the desired landing because the limit switches 30 and 31 are open during full-speed operation. The proper holding circuits, as previously traced, are maintained by relays 36 and 38, for upward travel, and by relays 35 and 37 for downward travel.

When it is desired to operate the elevator from one floor to the next adjacent floor, it is only necessary to momentarily actuate the car switch, and the car, of course, does not attain its maximum speed in the short distance to be traveled.

If, at any time, it is desired to operate the elevator in the ordinary manner, entirely under control of the car switch, the double-throw knife-switch 17 should be actuated to its upper position, whereupon the automatic operation of the floor relays and floor limit switches is prevented. Relay 82 becomes effective to retire the limit switches by maintaining coils 32 and 33 energized. This manual operation permits variable-voltage control that is, in the main, familiar to those skilled in the art and is employed in my system as a matter of convenience in cases of emergency operation.

Whereas, the so called levelling systems are not efficient in maintaining a fast schedule of elevator operation, compared to ordinary manual control by a skilled operator, my system of automatic control, in the hands of an unskilled operator, has been found to accomplish a considerable saving in time over all previous systems of control because of the fact that the car never overtravels or undertravels, with respect to any landing.

A further advantage secured by the use of my invention is the elimination of mechanical contact between the car and the speed switches or limit switches in the hatchway when slowing down from high speed. The noise and vibration of mechanical contact and occasional breakage of parts is avoided.

Obviously, modifications in my system will occur to those skilled in the art and I desire that my invention shall be limited only in accordance with the scope of the appended claims.

I claim as my invention:

1. In a control system for an elevator operable between a plurality of floors, motive means for moving said car, means for maintaining the speed of said motive means constant under varying load, means for starting said motive means and means for automatically initiating a stopping of said motive means at such points in the travel of said elevator as is required to decelerate and stop said elevator level with said floors.

2. In a control system for elevators operable between a plurality of floors, an elevator, variable voltage driving means for moving said elevator, having constant speed characteristics under varying load, means for starting said motive means, and means independent of said starting means for initiating a deceleration of said motive means at such points in the travel of said elevator as will permit said elevator to stop level with the floors regardless of the load on said elevator.

3. In a control system for elevators operable between a plurality of floors, multi-speed motive means for moving said elevator, means for maintaining the speed of said motive means constant under varying load, and means operable in correspondence with movements of said elevator for decelerating said motive means in steps of diminishing speed to cause said elevator to stop level with said floors.

4. In a control system for elevators operable between a plurality of floors, multi-speed motive means for driving said elevator, means for maintaining the speed of said motive means constant under varying load, and electromagnetic means operable in correspondence with movements of said elevator for decelerating said motive means in steps of diminishing speed to cause said elevator to stop level with said floors.

5. In a control system for elevators operable between a plurality of floors, multi-speed motive means for moving said elevator, means for maintaining the speed of said motive means constant under varying load, and means for decelerating said motive means in steps of diminishing speed to cause said elevator to stop level with said floors, said last named means comprising a switch, a coil normally ineffective to actuate said switch, means for rendering said coil effective to actuate said switch, and means for causing relative movement between said coil and said last named means in correspondence with movements of said elevator.

6. In a control system for elevators operable between a plurality of floors, multi-speed motive means for moving said elevator, means for maintaining the speed of said motive means constant under varying load, and means for decelerating said motive means in steps of diminishing speed to cause said elevator to stop level with said floors, said last named means comprising two elements, one including a switch and a coil normally ineffective to actuate said switch, the other comprising means for rendering said coil effective to actuate said switch, and means for mounting said elements for relative movement in correspondence with movements of said elevator.
15. 7. In a control system for elevators operable between a plurality of floors, multi-speed motive means for moving said elevator, means for maintaining the speed of said motive means constant under varying load, and means for decelerating said motive means in steps of diminishing speed to cause said elevator to stop level with said floors, said last named means comprising a switch, means for actuating said switch, means for rendering said actuating means ineffective, and means for causing relative movement between said actuating means and said means for rendering said actuating means ineffective, in correspondence with movements of said elevator.
8. In a control system for elevators operable between a plurality of floors, multi-speed motive means for moving said elevator, means for maintaining the speed of said motive means constant under varying load, and means for decelerating said motive means in steps of diminishing speed to cause said elevator to stop level with said floors, said last named means comprising a switch, means for actuating and maintaining said switch, means for rendering said actuating means ineffective, and means for causing relative movement between said actuating means and said means for rendering said actuating means ineffective, in correspondence with movements of said elevator.
9. In a control system for elevators operable between a plurality of floors, multi-speed motive means for moving said elevator, means for maintaining the speed of said motive means constant under varying load, and means for decelerating said motive means in steps of diminishing speed to cause said elevator to stop level with said floors, said last named means comprising a switch, magnetic means for actuating and maintaining said switch, means for rendering said actuating means ineffective, and means for causing relative movement between said actuating means and said means for rendering said actuating means ineffective, in correspondence with movements of said elevator.
10. In a control system for elevators operable in a hatchway between a plurality of floors, multi-speed motive means for moving said elevator, means for maintaining the speed of said motive means constant under varying load and means operable in correspondence with movements of said elevator for decelerating said motive means in steps of diminishing speed to cause said elevator to stop level with said floors, said last named means comprising a switch and a coil for actuating and maintaining said switch carried by said elevator, and a magnetizable plate carried by said hatchway for rendering said coil ineffective to maintain said switch in actuated position.
11. A control system for elevators comprising in combination, a hoisting motor, a reversing
- switch provided with a winding having a self-holding circuit, normally closed contactors in said self-holding circuit, and means to open said contactors having an energizing and a magnetizable element, said elements movable into and out of attractive relation by car movement, and effective when brought into attractive relation to open said contactors.
12. A control system for elevators comprising in combination, a car, a hoisting motor, a plurality of landings, up and down reversing switches having windings and self-holding circuits therefor, contactors in the self-holding circuit of the up switch, contactors in the self-holding circuit of the down switch, and means to actuate said contactors having a magnetizing and magnetizable element, said elements brought into and out of attractive relation by movement of the car.
13. A control system for elevators comprising in combination, a hoisting motor, a switch mechanism controllable manually to initiate car starts having a winding provided with a self holding circuit, said winding maintaining said switch mechanism closed independently of manual operation, contactors in said self-holding circuit, and means to actuate said contactors comprising magnetizing and magnetizable elements, said elements brought into and out of attractive relation by movement of the car.
14. A control system for elevators, comprising in combination, a switch closable manually having a winding and a self-holding circuit to maintain said switch closed independently of manual operation, contactors in said self-holding circuit, and means to actuate said contactors comprising an electro-magnet and a member magnetizable thereby, said elements movable into and out of attractive relation in accordance with car position.
15. A control system for elevators comprising in combination, a car start switch, a car stop switch, a reversing switch winding having a circuit responsive to said car start switch, a self-holding circuit for said winding, said stop switch being in said self-holding circuit, and actuating means for said stop switch having a magnetizing and magnetizable member movable into and out of attractive relation by movement of the car.
16. A control system for elevators comprising in combination, a hoisting motor, means to maintain a circuit therefor closed automatically comprising a switch having a winding provided with a self-holding circuit, contactors in said circuit, and actuating means for said contactors comprising a magnetizing and a magnetizable member movable into and out of attractive relation by car movement.
17. A control system for elevators comprising in combination, a hoisting motor, a reversing switch having a winding provided with a self-holding circuit, contactors in said circuit, and means to actuate said contactors comprising a magnetizable and a magnetizing element movable into and out of attractive relation by car movement.
18. A system of control for elevators, comprising in combination the car, motive means, control means comprising contactors effective to cause stop of the motive means but ineffective to cause start thereof, and actuating means for said contactors having a winding energizable to predetermine car stop and means controllable in accordance with car position to form a path

for the magnetic lines of said winding so that the latter when energized is effective to actuate said contactors only when in attractive relation with said means.

5 19. A control system for elevators comprising in combination, a hoisting motor, a switch mechanism having a winding energizable man-

ually, said winding having a self-holding circuit, and means effective to open said self-holding circuit comprising an electro-responsive switch part stationary and part movable in accordance with car movement. 5

EDGAR M. BOUTON.
